UNITED STATES PATENT OFFICE

HOLMAN H. LINN, OF MORRIS, NEW YORK, ASSIGNOR TO THE LINN MANUFACTURING CORPORATION, OF MORRIS, NEW YORK, A CORPORATION OF NEW YORK

LOGGING BOLSTER

Application filed February 20, 1930. Serial No. 429,992.

In log transportation, and without regard to the type of vehicle, side stakes are employed to hold the logs on the vehicle. They are mounted so as to be removably supported 5 in log-holding position and are associated with means under manual control capable of releasing them to permit the logs to roll off the vehicle. The stakes, when released from log holding position, are capable of swing- 10 ing movement outwardly and forwardly with relation to the platform of the vehicle; and although it has been proposed to effect the release from the far or clear side in order to avoid the hazard of injury to the operator, 15 such proposals suffer the disadvantage that where reduced to practice the holding means is not immune to entanglement with the logs, nor have the stakes been constructed and mounted so that in log discharge position 20 they may yield to an obstruction encountered by the moving vehicle and thus avoid break- age of the stakes.

Objects of the present invention are to provide stake-holding means capable of 25 facile release from the far side or the side of the vehicle opposite the released stakes; to provide stake-holding means which, when the stake is released, will be held in position to avoid any entanglement with the logs as 30 the vehicle is moved; so to construct and mount the stakes that, when in release position, they will yield to an obstruction; to provide for adjustment to permit different holding positions of the stake for the accom- 35 modation of large logs; to utilize the stake- holding means for directing the weight of the wedge log to make the log load very tight; and to direct the two outside logs towards the center of the load for tightening 40 up the load.

In the accompanying drawing

Figure 1 is a plan view, showing a single bolster or framing strut with stakes at the respective ends, and holding means embody- 45 ing my invention.

Fig. 2 is an end elevation of the same.

Fig. 3 is a side view of a single stake in discharge position and graphically showing the ability of the stake to clear a stump 50 or other obstruction.

Fig. 4 is a side view of the stake in log- holding position.

While the number of stakes, obviously, may vary, the description and showing, for simplicity, will be confined to a single pair. 55

A transverse body framing strut or bolster 1 is provided at each end with a stake 2, which, save in the details hereinafter noted, may be of any approved construction. The bolster 1 is formed at its respective ends with 60 a stake-receiving pocket 3, preferably formed by the extension of the side bracing plates of the bolster, but in any event, including side walls 4. The stake has a hinge element or pivot section 5, more or less snugly fitting 65 between the side walls 4 of the pocket, and pivotally connected to such side walls by a bolt 6. The pivot section is thus capable of swinging in the longitudinal plane of the bolster, but in either raised or lowered position is held by the side walls 4 from other movement. The stake proper includes a body 7 of appropriate length, the lower end of 70 which provides spaced walls 8, which fit over the free end of the pivot section 5. A pivot bolt 9 unites the walls 8, and thereby the stake proper, and the pivot section 5, the direction of the pivot bolt 9 being at right angles to that of the pivot bolt 6. Thus the stake proper is capable of swinging in a direction at right angles to the swinging movement of the pivot section, and as the latter moves in the longitudinal plane of the bolster, the stake proper will swing at right angles to such plane, or longitudinally of 75 the vehicle body. 80

The relation of the walls 4 of the pocket 3, and the mounting of the pivot section and lower end of the stake proper in such pocket, is such, that when the stake is in upright or log-holding position, as shown in Fig. 4, the walls 8 thereof fit between the side walls 4 of the pocket, and the stake proper is held against movement on the pivot bolt 9. Contrariwise, when the stake is in lowered or log discharging position, the lower end of the stake proper, that is to say, the walls 8, are wholly free of the side walls of the pocket 3, and the stake proper is free to swing in a direction longitudinally of the 85 100

vehicle body, thus yielding in event of an obstruction, which otherwise would tend to break the stake. This feature is shown more particularly in Fig. 3.

5 The outer wall of the stake proper, at a convenient point above the bolster, is integrally formed, or provided with an upwardly-opening hook projection 10, designed to receive and support the holding means. The holding means is in the form of a chain or like flexible element 11, terminally secured at 12 to the side of the bolster, from whence it extends over the hook 10 and around the stake proper, and then through guides 13 on the opposite side of the bolster, and terminates near the end of the bolster in several aligned rings 14.

10 The holding means for the opposite stake is similarly arranged, though terminally connected and guided in a manner opposed to that of the first mentioned chain. Near each end of the bolster, and of course on opposite sides, is mounted a bracket 15, in which is pivotally mounted a lever 16, over 15 which one of the rings 14 of the chain is designed to be passed. The bracket 15 carries a pivotally supported keeper 17, to be passed over the free end of the lever 16, following the placement of the ring 14 and proper 20 movement of the lever to put it in the plane of the keeper. A short hand chain 18 is connected to the keeper, so that the latter may be operated at will in an obvious manner to release the free end of the lever 16 25 in order to free the connected ring 14 and thereby the particular chain 11. It will be noted that the holding lever 16 and complementary releasing means for each particular stake is located on the bolster at the 30 end remote from that stake. Thus, in releasing the stakes on one side of the vehicle, the operator will of necessity be on the opposite side of the vehicle and not exposed to falling logs.

35 45 Another merit of the stake-holding chain is that on both sides of the bolster, that is to say, to the fixed end 12 on one side and to the first guide 13 on the other side, it presents a more or less sharply inclined support, indicated at 19, for the outside logs, so that they tend to roll towards the center and tighten the load. Moreover, the manner 50 of supporting the chain from the bolster eliminates the menace of pendant portions 55 catching or fouling after the released logs.

The provision of a plurality of rings 14 at the engaged terminal of the chain, insures compensating or adjustable holding length of the chain, thereby to permit any practical 60 inclination of the stakes, when in holding position, to accommodate various size logs.

Having described my invention, I claim:

1. A vehicle body including a bolster, a pocket including side walls formed at the end 65 of the bolster, a stake including a pivot sec-

tion and a body section, means for pivotally connecting the sections, and means for pivotally mounting the pivot section of the stake in said pocket, the side walls of the pocket preventing relative movement of the body and pivot sections of the stake when the stake is in operative position.

2. The combination with a logging vehicle, of a pocket secured thereto, a stake section pivoted therein for swinging movement transverse the vehicle, and a stake proper pivoted to the stake section for swinging movement in a direction longitudinally of the vehicle, said pocket preventing longitudinal swinging movement of the stake proper 80 when the stake section is in a predetermined position in such pocket.

3. A vehicle body including a bolster, a stake mounted at each end of the bolster for swinging movement relative to the body, a chain for holding each stake in log holding position relative to the body, each chain being terminally secured at one end to the bolster passed around the stake and extended longitudinally of the bolster, a manually controlled chain holding lever mounted adjacent that end of the bolster opposite the particular stake and cooperating with the adjacent terminal of the chain, and guides on the bolster to support the chain intermediate the stake and lever, said guides serving to prevent the free end of the chain from depending substantially below the bolster following release of the chain by the lever.

4. A vehicle body including a bolster, a stake mounted for swinging movement at one end of the bolster, a stake holding chain terminally secured at one end of the bolster, passed around the stake and extended lengthwise the bolster, a manually operable lever cooperating with the last mentioned end of the chain, and guides on the bolster for the chain and serving to remain at all times in position to support the free end of the chain following its release from the lever, the chain lengths leading from the stake being inclined to influence the outer logs of the load.

5. The combination with a logging vehicle, of a stake made up of two sections, one section being pivotally mounted on the vehicle for bodily swinging in a plane transverse the vehicle, the other section being pivotally connected to the first mentioned section for swinging in a plane at right angles to the plane of movement of the stake as a whole, the pivotal mounting of the stake as a whole permitting the stake to swing to an inoperative position with the pivotally mounted stake sections below the vehicle for swinging in a plane longitudinally of the vehicle.

6. The combination with a logging vehicle, of a stake including two pivotally connected sections, means for pivotally connecting one of the sections to the vehicle, said means preventing other than a movement of the stake

transverse the vehicle, the pivotal connection between the sections permitting relative movement of the sections in a plane longitudinally of the vehicle when the stake as a whole is moved to an inoperative position below the vehicle.

7. In a logging vehicle having a body, a two-part stake, the main section being pivoted to the body for swinging movement of the entire stake in a plane transverse the body, the remaining section of the stake being connected to the main section for swinging movement in a plane longitudinally of the body, the pivotal mounting of the main section causing the stake to move to an inoperative position in part pendant below the body, whereby in such position the longitudinally swinging section protects the stake against breakage in movement of the vehicle.

20 In testimony whereof I affix my signature.
HOLMAN H. LINN.
